(57) **CLAIM**

The ornamental design for a self-adjusting locking pliers and claw hammer combination, as shown.

DESCRIPTION

FIG. 1 is a perspective view of a self-adjusting locking pliers and claw hammer combination showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

1 Claim, 5 Drawing Sheets

FIG. 1

FIG. 2

FIG. 3

FIG. 5

FIG. 6

FIG. 7
